UNITED STATES PATENT OFFICE.

WILLIAM TAG AND SANFORD C. SMITH, OF PHILADELPHIA, PENNSYLVANIA.

ELECTRIC CIGAR-LIGHTING DEVICE.

SPECIFICATION forming part of Letters Patent No. 399,168, dated March 5, 1889.

Application filed July 18, 1888. Serial No. 279,809. (No model.)

To all whom it may concern:

Be it known that we, WILLIAM TAG and SANFORD C. SMITH, citizens of the United States, residing in the city and county of Philadelphia, State of Pennsylvania, have invented a new and useful Improvement in Electric Cigar-Lighting Devices, which improvement is fully set forth in the following specification and accompanying drawings.

10 Our invention consists of improvements in electric cigar-lighters, hereinafter described, and set forth in the claims.

We are aware that it is old in gas-lighting devices to attach a wiping-electrode to a gas-cock and to connect such wiping-electrode to one pole of a battery, while the tip of the burner is provided with a stationary contact device attached to the other pole of the battery, the relations being such that upon turning on the gas the wiping-electrode comes in contact with the stationary electrode, producing a spark, and thereby igniting the gas. The novelty of our invention lies in the adaptation of such electrodes with a novel form of 25 cigar-lighting apparatus.

Figures 1 and 2 represent perspective views of a cigar-lighting apparatus embodying our invention, Fig. 2 being partly in section. Figs. 3 and 4 represent detail views.

30 Similar letters of reference indicate corresponding parts in the several figures.

Referring to the drawings, A represents a section of gas-pipe made up of two angular parts, B and C, the lower one of which, C, carries the cock D and the wiping-electrode E, attached thereto by an insulated collar, F. The nipple or upper end of the burner H constitutes the electrode, against which the wiping-electrode contacts, as will be understood 40 upon inspection of the drawings.

In Fig. 3 we have shown an enlarged view of a nipple provided with a grooved guide-lip, a, adapted to guide the wiping-electrode E to the center of the burner before it releases it, 45 so that the spark will be made directly over

the jet of gas as it is turned on. To the lower end of this nipple or burner is attached a weighted handle, G, such as is well known in devices of this character. One pole of the battery (not shown) is connected by a wire, J, 50 to the insulated collar F, carrying the wiping-electrode, the other pole thereof being connected directly to the upper section of gas-pipe by another wire, so that the circuit from said battery is through the wiping-electrode 55 and the nipple, when the apparatus is lifted, by way of the gas-pipe to and through the wire J.

The operation will be understood upon inspection of the drawings, it being of course 60 understood that when the lighter is hanging in its normal position the electrodes are out of contact and the gas entirely turned off.

The two sections of pipe B and C are joined together at an angle, as shown, so as to make 65 the apparatus compact and to give to the wiping-electrode the necessary protection and security.

Having thus described our invention, what we claim as new, and desire to secure by Letters Patent, is—

1. In an electric lighter, a gas-pipe carrying a movable wiping-electrode, in combination with a cock and a tip, the latter having a groove, substantially as described. 75

2. In a gas lighter, a burner-tip constituting one electrode and having a guiding lip or groove adapted to guide the sliding electrode or wiper over the gas-jet, substantially as described. 80

3. A gas-lighter device having a fixed electrode and a wiping-electrode, the former being provided with a guide adapted to guide the contacting end of the wiping-electrode over the gas-exit, substantially as described. 85

WILLIAM TAG.

SANFORD C. SMITH.
